[57] CLAIM

The ornamental design for a sod plugger, as shown and described.

DESCRIPTION

FIG. 1 is a perspective view of the sod cutter showing my new design;

FIG. 2 is a top plan view thereof;

FIG. 3 is a front elevational view thereof, the rear elevational view being a mirror image thereof;

FIG. 4 is a side elevational view thereof, the opposite side being a mirror image thereof; and,

FIG. 5 is a bottom plan view thereof.

FIG. 1

FIG. 2

FIG. 3

FIG. 4

FIG. 5
